UNITED STATES PATENT OFFICE.

ANDREW L. RIKER, OF BRIDGEPORT, CONNECTICUT, ASSIGNOR TO THE "LOCOMOBILE" COMPANY OF AMERICA, OF NEW YORK, N. Y., A CORPORATION OF WEST VIRGINIA.

REGULATING MEANS FOR INTERNAL-COMBUSTION ENGINES.

1,136,368.

Specification of Letters Patent. Patented Apr. 20, 1915.

Application filed June 10, 1905. Serial No. 264,579.

To all whom it may concern:

Be it known that I, ANDREW L. RIKER, a citizen of the United States, residing at Bridgeport, in the county of Fairfield and 5 State of Connecticut, have invented an Improvement in Regulating Means for Internal-Combustion Engines, of which the following description, in connection with the accompanying drawings, is a specification, 10 like letters on the drawings representing like parts.

My invention relates to regulating means for internal combustion engines, being more particularly concerned with means for regulating and controlling the supply of gaseous mixture to the cylinders of the engine during the operation thereof.

My invention will be best understood by reference to the following description when 20 taken in connection with the accompanying illustration of one illustrative specific embodiment thereof, while its scope will be more particularly pointed out in the appended claims.

25 In the drawings,—Figure 1 is a plan view of a fuel and air mixing and controlling device embodying one form of my invention; Fig. 2 is a section on the line 2—2, Fig. 1; Fig. 3 is a section on the line 3—3, in Fig. 30 1, and, Fig. 4 is a modified form of an admission valve.

In the drawings I have shown one form of my invention as applied to a carburetor, intended herein specifically for supplying an 35 appropriate mixture of air and gaseous fuel to a multiple cylinder explosion engine, of an automobile the branched admission pipes for which are shown at A. The liquid gaseous fuel which is carried in a reservoir suitably located (not herein shown) first enters 40 the separator b through the passage b', which is connected to the fuel reservoir by an appropriate conduit (not shown) and, passing through the openings b² in the inner tubular sleeve b³, it rises through the valve-controlled passage b⁴ into the float chamber a. A cock b⁵ permits any separated water to be drawn off from the bottom 45 of the separator chamber.

50 A ball valve a' controlling the passage b⁴, is secured to the lower end of a valve stem a² which rises through the float chamber and

has threaded upon its upper end a stop guide a³ which guides the valve in its vertical movements. Loosely surrounding the valve 55 stem a² is the float a⁴ which rises with the fuel in the said chamber and when the fuel reaches the proper level therein, said float contacting with the bottom of the stop guide a³ will lift the valve stem and its valve to 60 close the valve opening b⁴ and cut off further admission of fuel; the level of fuel in the float chamber thus maintained by the float may be regulated at will by the threaded adjustment of the guide on the valve stem, 65 since the position of the said stop guide on the said valve stem determines the level at which the float will lift the valve to cut off further admission of the fuel.

The protruding end of the valve stem a² 70 is shown inclosed in an inverted cup a⁵ perforated at its top to receive the vertical sliding starting device a⁶ normally retained in its elevated position by the spring a⁷. By depressing this starting device the valve 75 stem may be manually depressed to open the valve and admit additional fuel to the float chamber for starting the engine, as will hereinafter be referred to. In order to permit the ready manipulation of the starting 80 device, I have shown the same controlled by the arm c of a bell crank lever, the other arm of which c', is connected to the push rod c². The engine with its attached carburetor will ordinarily be mounted in front of the dash 85 board of an automobile, which I have here indicated at d in Fig. 2 and said push rod c² therefore protrudes through the dash board and presents at the opposite side thereof an end c³ conveniently shaped for manipulation by the operator. A spring c⁴ normally holds the lever c out of pressing contact with the starting device a⁶. At or near the bottom of the float chamber a is an outlet passage a⁸ which communicates with an annular 90 chamber e surrounding the atomizing nozzle e' screwed into the bottom of the atomizing chamber E. This atomizing nozzle e' has a vertical axial passage e², with which the outlet passage a⁸ communicates through one or 95 more side openings e³.

The atomizing nozzle e' is provided with an exteriorly tapered end which extends into an enveloping deflecting cap f in the shape

of a truncated cone, the said cap being secured to and depending from the inner walls of the atomizing chamber E. The atomizing chamber is provided near its lower end with 5 an air inlet g through which a supply of air enters through the laterally arranged conduit g' and in practice I preferably connect the conduit with an air admission pipe which is artificially heated by the engine exhaust thereby to heat the exterior air admitted to the atomizer. These connections it is 10 unnecessary to show.

Above the atomizing chamber and having communication therewith through the opening e⁴ is located the cylindrically shaped mixing chamber H. The latter also has communication with the branched admission pipes A through suitable ports h these being formed in a sleeve or bushing h' fitted in the 15 mixing chamber H. The opposite side of the bushing is also cut away at e⁴ to form an admission port from the atomizing chamber and admission to and exit from the mixing chamber through the said ports e⁴ and h is 20 controlled by an appropriately formed piston valve h² slideable within the said bushing h' sliding movement being given thereto through the valve actuating rod h³. Any 25 suitable means may be employed for moving the valve but I prefer to connect the actuating rod h³ to an engine driven speed governor (not shown) whereby the valve is 30 moved as the engine speed changes and the quantity of fuel supplied to the engine varied automatically and in response to the 35 changing requirements for the same. The opposite end h⁴ of the actuating rod is extended through the opposite end of the mixing chamber where it may be carried 40 through the dash board of the vehicle and connected to a suitable operating lever whereby the operator may exercise manual control over the mixture throttling valve to supersede the governor control thereof at 45 any desired time and particularly on starting the engine.

During the operation of the engine the movements of the pistons therein in a manner well understood by those conversant 50 with the operation of internal combustion engines will create a sufficient vacuum to draw air inward through the air inlet g, thence upward within the deflecting cap f through the outlet e⁴ and into the mixing 55 chamber H and into the branched admission pipes A, drawing from the nozzle e the liquid fuel which is maintained therein at a level with that of the fuel in the float chamber a which level preferably is slightly below the top of the atomizer nozzle.

The depending cone-shaped cap f concentrates the draft of air about the nozzle and intensifies the atomizing action so that the air which leaves the atomizing chamber is

thoroughly saturated and mixed with the 65 vaporized fuel.

As the atomizer draws the fuel from the float chamber a, the float recedes with the level of the fuel therein and opens the valve a' to admit a further supply of fuel, the action being such that in practice the float maintains the valve normally open sufficiently to insure a substantially continuous admission of fuel both to the float chamber and also to the atomizing chamber E. 75

To start the engine when there is no vacuum therein to draw the air and fuel from the atomizing chamber, the push rod c² is pressed inward causing the depression of the starting device a⁶, thereby depressing 80 the valve stem a² and opening the valve a' to permit the fuel gravitating from the higher level in the reservoir to rise in the float chamber a sufficiently to overflow the top of the atomizer nozzle e' in the atomizing 85 chamber E. Movement of the engine pistons which may be produced by the hand rotation of the engine crankshaft can then be made to draw air through the inlet opening g, thereby causing the same to take up the 90 overflow fuel and furnish a sufficient supply of gaseous mixture to set the engine in motion and throwing into action the sparking devices.

The mixture of air and vapor as it comes 95 from the atomizing chamber is richer in fuel than is required and has to be diluted with a further mixture of air. To accomplish this, I have provided means for admitting air in proper quantity to the mixing chamber H, 100 where it is permitted to mingle with the carbureted air from the atomizing chamber, the diluted mixture passing to the engine cylinders; I have herein so constructed this auxiliary air admission supply that it takes 105 place automatically being proportioned to the requirements and running conditions of the engine. For this purpose I have provided an air admission chamber k in the casting K the latter secured to the top of the 110 casting in which is formed the mixing chamber H, there being free communication between said air mixing chamber and the auxiliary air admission chamber k.

The casing K is provided with an upright 115 cylindrical cap portion k' having for admission of the exterior air a plurality of triangular admission openings k² controlled by a vertically sliding piston valve k³, so that the continued depression of the said 120 valve will uncover a rapidly increasing admission area.

The piston valve k³ is secured to a sleeve k¹⁴ slideable on the stationary vertical tube k⁵ and normally pressed upward by the spring k⁶ against an abutment k⁶ formed by the walls of the cylindrical portion k'. Secured to the sleeve k¹⁴ and freely movable

with the piston k^3 within the chamber k is the plate or disk k^7 , the outside diameter of which is somewhat less than the inside diameter of the chamber k and which acts in the manner hereinafter described to regulate the admission of the auxiliary supply.

During the operation of the engine the valve k^2 will be moved by the actuating rod k^3 and the speed governor to a position determined by the speed of the engine, which position by appropriate design and adjustment may be made to furnish from the atomizing chamber the precise quantity of carbureted air desired and needful for that particular engine speed. The position of the valve will determine the actual or aggregate amount of fuel and therefore the richness of mixture furnished the engine under the particular conditions which hold at any particular time.

The amount of dilution of the carbureted air before it passes to the engine cylinders depends on the amount of air supplied through the auxiliary air supply to the mixing chamber. The amount of auxiliary air needed will of course be greater as the engine speed increases and the cylinders required to be filled and emptied a greater number of times. The actual dilution of the mixture is also required to be greater and an additional auxiliary air supply needed at higher speeds because a weaker mixture is required at high speeds than low speeds for most efficient working. In the present construction the proper increase or decrease in the auxiliary supply as the engine speed changes is automatically effected in accordance with the requirements of the engine for increase or decrease in speed and will be attended by an increase or decrease in the suction created by the engine piston and this suction acting within the auxiliary air chamber k upon the lower side of the plate k^7 will tend to vary the position of the latter according to the speed of the engine and cause thereby the depression or elevation of the piston valve k^3 and the increase or diminution in the supply of air through the ports k^2 . On increase in speed the valve will continue to move downward to give increased air supply until a condition of balanced pressure is reached between the opposite sides of the plate or disk k^7 , and this condition is allowed when the auxiliary air supply satisfies the requirements of the engine and not until then. If a lesser auxiliary air supply is required, as by a drop in engine speed, the consequent reduction in the suction of the engine acting upon the plate k^7 will move the valve k^3 automatically to close the ports k^2 until the exact condition of air supply required is attained. The auxiliary air valve thus acts automatically to maintain the auxiliary air supply at the re-

quired amount, this being accomplished independently of the action of the throttling valve k^2 , which may therefore be adjusted to give any and the exact desired quantity of fuel suited for each and every speed.

The auxiliary air supply in entering the ports k^2 passes downward through suitable openings in the bottom of the piston valve k^3 in the direction of the arrows and about the edges of the controlling plate k^7 , thence downward through openings in the grid k^8 which supports the valve spring k^4 , thence into the mixing chamber H , where it intermingles with the carbureted air.

In Fig. 4 there is shown a modified form of inlet valve which may be used, if desired, in place of the inlet valve described. This comprises the inlet casing L , which may be screwed into the mixing chamber H , the top of the casing having a cap l , threaded therein. The cap has a central opening which may be closed by the plate valve l' engaging a seat formed on the lower side of the cap. The valve is provided with a stem l^2 , slidable in a bearing l^3 , which is carried by a spider formed upon the cap. The valve is normally held to its seat by the spring l^4 , acting against the washer l^5 , which is adjustably secured to the valve spindle. On a decrease of pressure within the casing L , the valve l' tends to open and admit the necessary supply of air, maintaining such supply so long as is requisite.

While I have here shown and described with particularity one embodiment of my invention, it is to be understood that the same is submitted for illustrative purposes only, the invention being susceptible of many changes, modifications and other applications unnecessary here to mention.

Claim.

1. An air supplying device for the carbureter of an internal combustion engine, comprising auxiliary air-supplying means having an auxiliary air-supplying chamber having one or more air inlet openings, a valve controlling the admission of air through said openings, said valve being shaped to present an increasing area to the admission of air in the direction of opening movement of the valve, means normally pressing said valve toward a closed position and a plate connected with said valve to move the same against the action of the valve-closing means, said plate partially obstructing the passage of the admitted air through the said chamber and being exposed on its inner face to the suction created by the engine.

2. An air and fuel mixing device for internal combustion engines comprising means for supplying carbureted air, a mixing chamber in communication with said means, means to admit additional air to said mix-

- ing chamber and a common valve independent of said additional air admitting means controlling the entrance and discharge from said mixing chamber.
5. 3. An air and fuel mixing device for internal combustion engines comprising means for supplying carbureted air, a mixing chamber in communication with said means, a suction controlled valve to admit additional air to said mixing chamber and a piston valve controlling the entrance to and discharge from said mixing chamber.
10. 4. An air and fuel mixing device for internal combustion engines comprising means for supplying carbureted air, a mixing chamber in communication therewith, a valve for controlling the entrance to and discharge from said mixing chamber and provisions whereby said valve may be operated either automatically or manually.
15. 5. An air and fuel mixing device for internal combustion engines comprising a mixing chamber for the carbureted air, auxiliary air supplying means connected with said chamber and having air admission openings, a valve normally closing said openings, said openings being of gradually increasing area in the direction of opening movement of the valve, the latter having an attached disk interposed between said openings and said mixing chamber and about which the additional air supply passes to said mixing chamber, said disk being exposed upon its inner face to the suction 35 created by the engine.
20. 6. An air and fuel mixing device for internal combustion engines comprising a mixing chamber, an engine driven governor-controlled valve for controlling the admission of carbureted air to said mixing chamber, an auxiliary source of air supply to said mixing chamber independent of said valve and comprising an auxiliary air chamber having valve controlled air inlet openings, 40 said openings being shaped to present for a given valve movement an increasing area to the admission of air in the direction of opening movement of the valve, said valve being exposed to the suction created by the 45 engine and operated thereby.
25. 7. An air and fuel mixing device for internal combustion engines comprising a mixing chamber, a throttle valve in said chamber, a controlling member secured to said valve and passing through one end of said chamber, a second controlling member 50 operatively related to said valve and passing through the opposite end of said chamber, means for supplying carbureted air to said chamber, and means dependent on the engine suction also for automatically furnishing an additional air supply to said chamber.
8. An air and fuel mixing device for internal combustion engines comprising a mixing chamber, a throttle valve in said chamber, controlling means including a part secured to said valve and passing through one end of said chamber, and a second part operatively related to said valve and passing through the opposite end of said chamber, means at one end of said chamber for supplying carbureted air thereto, an exit opening controlled by said throttle valve at the same end of said chamber, and an automatic air admission valve at the opposite end of said chamber.
10. 9. An air and fuel mixing device for internal combustion engines comprising a mixing chamber, means for supplying carbureted air to said chamber at one end thereof, an exit opening for said chamber adjacent the same end and aligned with the entrance opening, a throttle valve controlling said exit opening, and an automatic air valve at the opposite end of said chamber.
15. 10. The combination with means for supplying carbureted air of a mixing chamber, an auxiliary air supplying means connected with said chamber, the said means comprising an auxiliary air chamber having one or more air inlet openings, a valve controlling the admission of air through said openings, said valve being shaped to present an increasing area to the admission of air in the direction of opening movement of the valve, and a valve controlling wall connected to the valve and exposed to the fluid pressure both within and outside of said mixing chamber.
20. 11. An air and fuel mixing device for internal combustion engines comprising means for supplying carbureted air, a mixing chamber in communication with said means, a valve for controlling the entrance of carbureted air to said mixing chamber, and an automatic air valve for providing a supplemental supply of air to said mixing chamber.
25. 12. An air and fuel mixing device for internal combustion engines comprising means for supplying carbureted air, a hollow cylindrical valve serving as a mixing chamber and having perforated walls to present controlled ports for the admission of carbureted air from said means and the discharge of the mixture from said mixing chamber, and an automatic air valve controlling a supplemental supply of air having access to the interior of said valve through the open end thereof.
30. 13. An air and fuel mixing device for internal combustion engines comprising means for supplying carbureted air, a hollow cylindrical valve serving as a mixing chamber and having perforated walls to present controlled ports for the admission of carbureted air from said means and the discharge of

the mixture from said mixing chamber, an automatic air valve controlling a supplemental supply of air having access to the interior of said valve through the open end 5 thereof, and means for controlling both manually and automatically said cylindrical valve.

In testimony whereof, I have signed my name to this specification, in the presence of two subscribing witnesses.

ANDREW L. RIKER.
